United States Patent

Des. 236,673
Patented Sept. 9, 1975

236,673

COLLAPSIBLE TABLE

Ernst Ehrman, 400 E. 82nd St.,
New York, N.Y. 10028

Filed May 24, 1973, Ser. No. 363,660

Term of patent 14 years

Int. Cl. D6—03

U.S. Cl. D6—146

FIG. 1.

FIG. 2.

FIG. 4.

FIG. 3.

FIG. 5.

FIG. 6.

FIG. 7.

FIG. 1 is a perspective view of the table embodying my design;

FIG. 2 is a perspective view looking from a different angle than FIG. 1;

FIG. 3 is a bottom plan view of the table;

FIG. 4 is a front elevational view of the table of my design;

FIG. 5 is a view similar to FIG. 4 showing a modification thereof;

FIG. 6 is a view similar to FIG. 4 showing yet another modification; and

FIG. 7 is a view similar to FIG. 4 showing still another modification.

I claim:

The ornamental design for a collapsible table, as shown.
